UNITED STATES PATENT OFFICE

2,121,514

INCINERATOR

Arthur C. Waterman, Shreveport, La.

Application May 23, 1936, Serial No. 81,537

2 Claims. (Cl. 110—18)

This invention relates to an incinerator designed primarily for burning trash in small quantities, it being an object of the invention to utilize the heat from the burning trash for drying garbage when deposited in a special compartment provided therefor.

Another object is to mount the incinerator in a new and novel manner whereby it can be inverted readily for the purpose of delivering accumulated ashes, etc.

A still further object is to mount the incinerator so as to be supported normally in an upstanding position and off of the ground so that air is free to circulate around and under it at all times, thereby to keep it dry and cool so that it will not deteriorate rapidly.

A further object is to provide an incinerator which can be set up readily for use and will not readily get out of order.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

In the accompanying drawing the preferred form of the invention has been shown.

In said drawing

Figure 1 is a central vertical section through the incinerator, the position thereof while being dumped, being indicated by broken lines.

Figure 2 is a section on line 2—2, Figure 1, the lower portion being in elevation.

Figure 3 is a top plan view.

Figure 4 is a section on line 4—4, Figure 1.

Referring to the figures by characters of reference 1 designates the body of the incinerator which can be formed of any desired size or shape and of any suitable material, such as sheet metal. In the present case the body has been shown rectangular and secured to each side of it is an angular bracket 2 the upper portion forming an arm 3 extending beyond the front of the body. The two brackets are joined at their lower end by a cross bar 4 which extends under and serves to support the bottom of the body.

Posts 5 are suitably anchored in the ground and are preferably held in cement, as shown at 6, these posts being located in front of the body 1 and pivotally connected at their upper ends to the arms 3, as shown at 7. Thus under normal conditions the container or body 1 has the lower

portion of its front wall contacting with the posts 5 as shown so that the container is supported by gravity in an upstanding position. Handles 8 are suitably located on the walls of the container or body 1 whereby the same can be readily swung about the pivot 7 to the downwardly inclined or dumping position as shown by broken lines in Figure 1. However under normal conditions the body is supported in upstanding position as shown by full lines in said figure.

Extending transversely within the body 1 near the rear wall thereof but spaced therefrom is a foraminous partition 9 to the upper end of which is hingedly connected a lid 10 adapted to be seated by gravity on the walls of the container. That portion of this lid between the hinge 11 and the back wall of the container or body 1 is so proportioned that when the front end of the lid is swung upwardly as shown by broken lines in Figure 1, the back end thereof will swing downwardly into the space 12 provided between partition 9 and the back wall of the body 1. When the lid is closed, however, the upper end of this space will be covered thereby.

Partition 9 is inclined downwardly toward the front of the body and at its lower end there is a transverse pivot rod or other hinge member 13 on which is mounted a grate 14. This grate is preferably made up of side strips 15 connected by cross bars 16. The grate is normally supported in a substantially horizontal position by a supporting rod 17 connecting the sides of the body 1.

The space below grate 14 constitutes an ash and drying compartment 18.

Openings 19 are provided in the sides of the body 1 so that air is supplied to the interior of the body for the purpose of supporting combustion.

In using this incinerator the lid 10 is raised in any suitable manner, as by means of a handle 20 and ordinary trash is deposited in the body and on the grate 14. Wet material and garbage can be dropped into the space 12 while the cover is raised. After the trash has been ignited, the cover is lowered and the combustible material supported by the grate will be consumed while the heat therefrom will act to dry the garbage or other material which had been deposited in the space 12 and compartment 18. Heat is transmitted to the garbage by radiation and also by conduction through the walls of the incinerator which become intensely hot during the burning of trash.

When it is desired to empty the incinerator,

one or more of the handles 8 can be used for swinging the incinerator about the pivot 7, this being shown by broken lines in Figure 1. This movement will cause the cover or lid 10 to swing open while the grate 14 will also swing downwardly. Thus the loose contents of the body 1 will be released and gravitate into any container provided therefor beneath the open lower portion of the body. Thereafter the body can be 10 swung back to the position shown by full lines in Figure 1 at which time the lower portion thereof will swing against the posts 5 so that the body will be supported in an upstanding position.

It is to be understood that the body 1 can 15 be made cylindrical or of any other suitable shape and instead of providing two posts at the side for supporting the body, one can be used. It is also to be understood that the posts can be located at other points instead of in front 20 of the body. These changes are so obvious that it is not deemed necessary to illustrate or describe them in detail.

For the purpose of limiting the dumping action of the incinerator, a suitable stop 21 can be arranged in the path thereof. It will be understood, also, that openings for the admission of air can be located at suitable points below the level of the grate, as shown for example at 22.

What is claimed is:

1. An incinerator including a container, rigid means of supporting the same in an upstanding position, said container being movable relative to its supporting means to deliver its contents 5 by gravity, means in the container for dividing the interior thereof into a trash receiving space and a garbage receiving space, a hinged grate at the bottom of the trash receiving space and dividing such space from a compartment thereunder in communication with the garbage receiving space, said grate being adapted to swing downwardly toward and relative to the dividing means when the container is inverted.

2. An incinerator including a body, means for 15 supporting the body for swinging movement into an inverted position, a cover for the body, means in the body dividing the same into a trash receiving space and a garbage receiving space, said cover closing the upper end of both spaces under normal conditions and being movable to open both spaces simultaneously, a grate at the lower end of the trash receiving space and hingedly mounted, and a support for the grate when in normal position, said grate being adapted to 20 move out of normal position when the container is inverted.

ARTHUR C. WATERMAN.
